TUFTING ATTACHMENT FOR SEWING MACHINES

William F. Schmiedel, Oshkosh, Wis., assignor to
Deltex Rug Company, Oshkosh, Wis., a corporation of Wisconsin

Application May 5, 1934, Serial No. 724,104

9 Claims. (Cl. 112—79)

This invention relates to improvements in tufting attachments for sewing machines.

It is one of the objects of the present invention to provide a tufting attachment adaptable to a standard form of sewing machine and requiring relatively little modification of the sewing machine.

A further object of the invention is to provide tufting attachments of the character described which are motivated by means mounted directly on the main drive shaft of the sewing machine.

A further object of the invention is to provide a tufting attachment for sewing machines which is very simple and employs a minimum number of parts, and in which the strand looping member and cutting means are combined.

A further object of the invention is to provide a tufting attachment for sewing machines wherein the strand loop cutting means is arranged to sever the loops with a long drawing cutting motion instead of a chopping motion, whereby higher speed of operation is attained and wear on one point of the cutter is eliminated.

A further object of the invention is to provide an attachment of the class described wherein a previously engaged loop, or loops, on the looper are severed by a reciprocation of the looper in one direction and at the same time another loop is being engaged and formed.

30 A further object of the invention is to provide a tufting attachment for sewing machines having a cutter replaceably carried directly by the looper, permitting easy removal of the cutter for sharpening or for replacement.

35 A further object of the invention is to provide a tufting attachment for sewing machines having a vertically adjustable combination looper and cutter whereby the lengths of loops to be formed may be easily controlled.

40 A further object of the invention is to provide an attachment of the class described wherein the work supporting plate has attached to its lower surface, adjacent the needle slot, a serrated plate for the purpose of cooperating with another novel instrumentality in the engagement of the outwardly extending length of yarn to releasably hold it taut during the cutting movement of the cutter to relieve strain on the fabric through which the yarn has passed.

50 A further object of the invention is to provide a tufting attachment including a reciprocating bar adapted to releasably hold portions of the yarn of a loop against the above-mentioned serrated plate, whereby during cutting operations 55 of the cutter the pull will be against the yarn

and will not be imparted to, nor strain the fabric, as in the latter event, in the case of a dull cutter, loops might be pulled outwardly too far with respect to the surface of the fabric.

A further object of the invention is to provide 5 a tufting attachment of the character described including a novel form of fabric feeding foot which is arranged so as to gauge the rows of stitches with relation to the fabric, and which can straddle pairs of rows of stitches to properly 10 gauge the positions of intermediate rows of stitches.

A further object of the invention is to provide 15 a tufting attachment for sewing machines which is of very simple construction, is strong and durable and inexpensive, and which is well adapted for the purposes set forth.

With the above and other objects in view the invention consists of the improved tufting attachment for sewing machines, and its parts and 20 combinations as set forth in the claims, and all equivalents thereof.

In the accompanying drawings in which the 25 same reference characters indicate the same parts in all of the views:

Fig. 1 is a fragmentary end elevation of a sewing machine showing the improved tufting mechanism incorporated therein, portions of the base of the machine being in section;

Fig. 2 is a horizontal sectional view taken on 30 line 2—2 of Fig. 1 with certain cover plates removed;

Fig. 3 is a longitudinal vertical sectional view taken on line 3—3 of Fig. 2 with the cover plates 35 in position;

Fig. 4 is a fragmentary end elevation, partly in section, showing the relative positions of the needle, the cutter and looper, and the yarn pinching reciprocating bar at a certain position of the drive shaft of the machine;

Fig. 5 is a horizontal sectional view taken on 40 line 5—5 of Fig. 4 with a cover plate removed and another broken away;

Fig. 6 is an end elevation similar to Fig. 4 only showing the position of the mechanisms with 45 the needle in a lowered position;

Fig. 7 is a horizontal sectional view taken on line 7—7 of Fig. 6 with a cover plate removed and another broken away;

Fig. 8 is a detail sectional view taken on line 50 8—8 of Fig. 3; and

Fig. 9 is a fragmentary plan view of a portion of rug fabric showing how the feeding foot is utilized to gauge a row of stitching.

Referring now more particularly to the draw- 55

ings, it will appear that the sewing machine head is indicated generally by the numeral 12 and said head includes a base portion 13. Extended longitudinally below the base 13, mounted in suitable bearings, is an oscillatory drive shaft 14. Said drive shaft receives oscillatory motion from the usual pulley shaft 15 extending through the upper end of the head 12 by the following mechanism: The pulley shaft is driven by the usual pulley (not shown) mounted on its outer end, and the inner end of the pulley shaft, within the upper portion of the head, has fast thereon an end of a crank 16. The outer end of said crank has pivotally secured thereto the upper end of a crank arm 17 and the lower end portion of said crank arm is pivotally secured to a portion of a slotted casting 18, and said casting is mounted fast on an intermediate portion of a lower rocking stud shaft 19. The adjacent end of the drive shaft 14 has fast thereon an arm 20, and the other end portion of said arm carries a block 21 which is movably engaged within a slot 22 in the casting 18. Hence, when the pulley shaft is turned, through the before-described connections oscillatory movement will be imparted to the drive shaft 14.

Above the end of the base 13 opposite the head 12 there are mounted the usual vertical feeding foot and needle carrying rods 23, 24 and 25. The rod 23 carries an outer bifurcated element 26 of an improved feeding foot, while the rod 24 carries an inner foot element 27 adapted to be reciprocated in a horizontal path relative to the outer foot element 26. Also, during certain portions of the movement of said foot element 27 it is raised and lowered slightly with respect to the work supporting plate 28 over which it is disposed. Conventional means are employed for jointly reciprocating the rods 24 and 25 vertically and in a slightly orbital path. The lower end of the rod 25 carries a sewing needle 29 which is reciprocated by the rod orbitally vertically and through an opening 33 in the foot element 27, and through a needle slot 30 in the work supporting plate 28 and into close proximity to the serrated edge 31 of a yarn engaging plate 32 secured to the under-surface of the work engaging plate adjacent one edge portion of the needle slot 30.

Disposed below the base 13, transversely thereof and adjacent the needle slot 30, is a slotted supporting bracket 34. Within the slot thereof is slidably mounted a plate 35. One end portion of said plate has vertically adjustably secured thereto the depending portion 36 of a looper 37. The looper 37 projects substantially right angularly from the upper portion of the member 36 and said looper member has a shoulder 38 at its outer end portion. There is removably held to the looper 37, by means of a screw 39, a cutter 40, whose cutting edge is disposed at a slight angle with respect to the edge of the looper. The cutter terminates short of the shouldered portion of the looper but is arranged to form an angularly disposed extention of the effective edge of the looper. Secured to the opposite end portion of the plate 35 is a laterally offset needle guide 41.

As previously mentioned, the drive shaft 14 has an oscillatory movement imparted thereto. The end of said shaft 14 adjacent the looper mechanism has fast thereon a wheel 42. A block 43 is pivotally secured to the outer face of said wheel in an off-center relationship. Said block, while being free to move on its pivot 44, is slidably confined within a vertical slot 45 in a rear extension 75 of the looper slidable plate 35. Through this con-

nection, therefore, oscillatory movement of the shaft 14 is translated into reciprocatory movement imparted to the plate 35, which plate, carrying the combined cutter and looper, causes said member to move back and forth adjacent the 5 needle 29 and below the work supporting plate 28.

An important feature of the invention resides in the provision of a yarn strand pinching bar 46. This bar is slidably mounted longitudinally of the base 13 immediately below the top surface 10 thereof. Its end adjacent the looper 37 is formed with an offset 47 to position adjacent the inner edge of the yarn engaging plate 32. An inner portion of said pinching bar 46 carries on its lower surface a depending block 48 which is 15 longitudinally movable in a slot 49 in a lower supporting plate 50. The pinching bar is adapted to slide on the upper surface of said plate 50, between the same and the work supporting plate 28 of the base 13. Mounted fast on the drive 20 shaft 14, below the block 48, is a cam 51 having an eccentric cam groove 52. A cam roller 53 is adapted to ride in said cam groove and said roller is carried by a pin 54 depending from the pinching bar block 48. The cam groove is so 25 shaped, that through the connections with the pinching bar 46, when the needle 29 is in the raised position shown in Fig. 3, the end 47 of the pinching bar will be away from the plate 32. However, when the needle is in an intermediate 30 position with the looper-cutter 37 drawing away from the needle to sever a loop or loops, the pinching bar moves outwardly to pinch yarn strands between it and the plate 32, as shown in Figs. 4 and 5. During continued travel of the 35 needle the pressure foot 26 reciprocates to move the fabric and during this period the cam 51 causes a quick short movement of the pinching bar away from the plate 32 so as to release the yarn, as shown in Figs. 6 and 7.

A piece of fabric 55, of a predetermined size to form a rug, is positioned on the base 13 and work supporting plate 28 and the strand of yarn 56, or other material to be used, is threaded through the needle 29 and when sewed through the ma- 45 terial and cut forms the pile of the rug.

The outer free end of the looper is beveled, as shown in Fig. 2, to permit easy entrance between the needle side and the strand in forming the loops, and the shoulder 38, at the outer end of 50 the looper, prevents the loops from slipping off when the looper is reciprocated rearwardly. In the formation of a loop the yarn 56 has an upwardly extending portion which engages a notch in the plate 32 and this means serves to hold a 55 formed loop tightly on the looper and prevents slippage when the looper and feed reciprocate forwardly during upward reciprocation of the needle. Also, the engagement of the yarn with said plate is important in connection with the 60 pinching operation of the pinching bar during loop cutting operations, as previously described.

In operation, the needle 29 having the strand threaded therethrough reciprocates downwardly through the fabric and through the needle-slot 65 30 of the plate 28. At the lower end of its reciprocation the needle enters the space adjacent the inner face of the needle guide 41 to prevent any lateral flexure of the needle. The upward movement of the needle will cause the yarn to slacken, 70 and at the same time the looper plate, carrying the looper and cutter, will move forwardly, to cause the outer end of the looper to move between the strand and the needle to a point where the looper shoulder 38 has passed beyond the 75

strand. As the needle rises out of the fabric, the feeding members 26 and 27 operate to push the fabric rearwardly and the looper frame also reciprocates rearwardly, during which time the upwardly extending strand portions of the loop are engaged by the serrated plate 32. Also, during this period there is the reciprocation of the pinching bar 46, previously described in detail. After reaching its highest point the needle starts downwardly and at the lowest point of the needle, the looper frame starts to move forwardly. During reciprocations of the looper frame a loop on the looper is crowded onto the cutter 40 while another loop is being formed, and reciprocation of the cutter serves to successively sever each loop thus moved onto the cutter. During the severing operation the pinching bar 46 is effective to tightly clamp the loop strands against the plate 32 so as to prevent any direct strain on and pull against the fabric through which the loops are passed. The cutting of the loops is accomplished with a relatively long drawing action of the cutter. The action of the combined looper and cutter is such that certain inner loops are being cut while a subsequent loop is being engaged and held. The cut loops form tufts on the fabric and as the work progresses said tufts move rearwardly in the elongated needle slot and are accommodated thereby. When the tufts reach the end of the needle slot they are withdrawn therefrom by the rearward movement of the fabric.

In Fig. 9 a fragmentary plan view of the fabric 55 with a plurality of lines of yarn stitching thereon is disclosed. In sewing the yarn through the fabric the operator initially sews a longitudinal line of stitching 57 and then when the next line is to be sewed the feeding foot is arranged relative to the completed line so as to space the next line to be sewed, 58, and this performance is repeated. It will be noted that the lines of stitching 57, 58, 59 and 60, gauged by this means, are spaced apart a substantial distance and in order that the tufts or piles to be produced may be close together, it is necessary to sew lines of stitching intermediate the first sewed lines 57, 58, 59 and 60. For this purpose the improved two-part feeding foot 26-27 performs an important function. The structure of said feeding foot is such that it may be used to accurately gauge the position of intermediate rows. As shown in Fig. 9 when an intermediate row 61 is to be sewed the member 26-27 is positioned so that the legs of the portion 26 straddle a pair of spaced rows of stitching 59 and 60 with said rows of stitching extending in the space between inner side portions of the member 26 and outer side portions of the other foot element 27. This therefore accurately locates the position of intermediate row 61 and in this manner any number of intermediate rows may be readily gauged and located.

As previously brought out the cutter 40 may be easily removed from the member 37 for sharpening or replacement, and by shifting the member 37 vertically relative to the bar 35 the length of the loops and tufts may be easily varied, as desired.

It will be further understood that a number of said tufting attachments may be mounted on the same sewing machine to permit sewing a plurality of rows of stitches at the same time.

From the foregoing description it will be seen that the improved tufting attachment is of simple and novel construction, requires little modification of a standard sewing machine, and is well adapted for the purposes described.

What I claim as my invention is:

1. A tufting attachment mechanism for sewing machines having a reciprocating needle for penetrating a fabric and carrying a strand which is passed through the fabric by the needle, comprising a transversely reciprocal frame positioned below the fabric and carrying a looper arm and a cutter adjacent an edge portion of the looper arm, the looper arm being arranged to engage the strand to form loops below the fabric, means for reciprocating the needle and the frame member, the cutter being arranged to sever a previously formed loop during reciprocation of the frame while another loop is being formed and engaged on the looper arm, and rectilinearly reciprocating means independent of the looper for engaging a portion of the yarn of a loop during reciprocations of the frame member and the needle and for releasing it during other reciprocations of the frame member and needle. 20

2. A tufting attachment mechanism for sewing machines having a reciprocating needle for penetrating a fabric and carrying a strand which is passed through the fabric by the needle, comprising a transversely reciprocal frame positioned below the fabric, a looper arm having a lower engaging edge portion and vertically adjustably carried by said frame, a cutter adjustably and removably carried by said frame adjacent the looper arm and forming an angular continuation of the lower edge thereof, the looper arm being arranged to engage the strand to form loops below the fabric and the cutter being arranged to cut a previously formed loop engaged by the arm during reciprocation of the frame member, means for engaging portions of formed loops during the cutting reciprocations, and means for reciprocating the needle and the transverse frame member.

3. A tufting attachment mechanism for sewing machines having a reciprocating needle for penetrating a fabric and carrying a strand which is passed through the fabric by the needle, comprising a transversely reciprocal frame positioned below the fabric, a looper arm having a lower engaging edge portion and vertically adjustably carried by said frame, a cutter adjustably and removably carried by said frame adjacent the looper arm and forming an angular continuation of the lower edge thereof, the looper arm being arranged to engage the strand to form loops below the fabric and the cutter being arranged to cut a previously formed loop engaged by the arm during reciprocation of the frame member, reciprocating pinching means for engaging portions of formed loops during the cutting reciprocations, and means for reciprocating the needle, the transverse frame member, and the pinching means. 55

4. A tufting attachment mechanism for sewing machines having a reciprocating needle for penetrating a fabric and carrying a strand which is passed through the fabric by the needle and a slotted work supporting plate through which the needle reciprocates, comprising a transversely reciprocal frame positioned below the fabric and carrying a combination looper arm and a cutter adjacent an edge portion of the arm, the cutter being inwardly of the looper arm, the looper arm being arranged to engage the strand to form loops below the fabric, means for reciprocating the needle and the frame member, the cutter being arranged, while reciprocating, to engage and to sever a previously formed loop moved relative to the cutter while another loop is being formed and engaged on the looper arm, there being sta- 75

- tionary means below said work supporting plate for engaging and holding a portion of the yarn of a loop taut during reciprocation of the frame member and the needle, and moving means co-
 5 operable with said stationary means for pinching a portion of the yarn of a loop only during severing movements of the cutter.
5. A tufting attachment mechanism for sewing machines having a reciprocating needle for penetrat-
 10 ing and carrying a strand through a fabric, comprising transversely reciprocal shouldered means below the fabric for forming the strand into loops, a cutter rigidly carried by the reciprocating means inwardly of the shouldered means, for severing loops moved from the shouldered means onto the cutter while another loop is being formed and engaged on said shouldered means, pinching means momentarily engaging portions of the formed loops, and means for reciprocating
 15 the needle, the transverse member, and the pinching means in timed relationship.
6. A tufting attachment for sewing machines having a reciprocating needle for penetrating and carrying a strand through a fabric and a reciprocating drive shaft, comprising a reciprocal looper-cutter below the fabric for forming the strand into loops and for severing the loops, a reciprocal pinching bar for releasably engaging strand portions of loops below the fabric while said loops
 20 are being severed, and means on said drive shaft for reciprocating the looper-cutter and the pinching bar in timed relationship so that the pinching bar is moved to pinching position while the looper-cutter is moved away from the needle.
7. In a sewing machine having the usual needle, work feed, means for guiding a strand to the needle, and reciprocating drive shaft, a fabric supporting plate having an elongated needle slot, a plate having a notched edge mounted below the
 25 supporting plate with the notched edge adjacent the needle slot, the needle reciprocating through the slot and fabric and adjacent said notched edge to successively carry the strand through the fabric and below the supporting plate, a reciprocal pinching bar mounted below said supporting plate with an end portion adjacent the notched edge of said plate, a looper-cutter member below the plate opening and arranged to successively pass into and engage loops formed during upward reciprocations of the needle and to cut formed and engaged loops, a reciprocation of the needle and an advance movement of the work feed caus-
 30 ing the strand to slacken and shift on one side of the needle and to engage in a notch of said plate, and means for reciprocating the needle, the looper-cutter member, and the pinching bar, the reciprocation of the pinching bar being toward and against the notched plate to engage a strand 5 during cutting reciprocations of the looper-cutter, and away from said notched plate to release the strand during advance movements of the work feed.
8. A tufting attachment mechanism for sewing machines having a reciprocating needle for penetrat-
 10 ing a fabric and carrying a strand which is passed through the fabric by the needle, comprising a transversely reciprocal frame positioned below the fabric and carrying a looper arm and a 15 cutter adjacent an edge portion of the looper arm and inwardly of the end thereof, the looper arm and cutter extending longitudinally of the line of feed for the sewing machine, and the looper arm being arranged to engage the strand to form 20 loops below the fabric, means for reciprocating the needle and the frame member whereby a loop is engaged by the cutter and is severed thereby while another loop is being formed and engaged on the looper arm outwardly of the cutter, and 25 reciprocating means independent of the looper for engaging a portion of the yarn of a loop during reciprocations of the frame member and the needle.
9. A tufting attachment mechanism for sewing machines having a reciprocating needle for penetrat-
 30 ing a fabric and carrying a strand which is passed through the fabric by the needle, comprising a transversely reciprocal frame positioned below the fabric and carrying a combination 35 looper arm and a cutter adjacent an edge portion of the looper arm, said looper arm and cutter extending longitudinally of the line of feed for the sewing machine and having an outer looper arm portion arranged to engage the strand to 40 form loops below the fabric and an inner cutter portion to engage loops moved inwardly of the looper arm during reciprocation of said member, means for reciprocating the needle and the frame member, the cutter being arranged to sever a 45 previously formed loop during reciprocation of the frame while another loop is being formed and engaged on the looper arm, and reciprocating means independent of the looper for pinching a portion of the yarn of a loop below the fabric 50 during reciprocations of the frame member and the needle.

WILLIAM F. SCHMIEDEL.
